(57) **CLAIM**

The ornamental design for a flange part for medical irrigation tube, as shown and described.

DESCRIPTION

FIG. 1 is a front view of a flange part for medical irrigation tube.

FIG. 2 is a rear view of the flange part for medical irrigation tube.

FIG. 3 is a top plan view of the flange part for medical irrigation tube.

FIG. 4 is a bottom plan view of the flange part for medical irrigation tube.

FIG. 5 is a left side view of the flange part for medical irrigation tube.

FIG. 6 is a right side view of the flange part for medical irrigation tube.

FIG. 7 is a perspective view of the flange part for medical irrigation tube.

FIG. 8 is an enlarged front view of the flange part for medical irrigation tube, the rear view being identical thereto.

FIG. 9 is an enlarged top plan view of the flange part for medical irrigation tube.

FIG. 10 is an enlarged bottom plan view of the flange part for medical irrigation tube.

FIG. 11 is an enlarged left side view of the flange part for medical irrigation tube, the right side view being identical thereto.

FIG. 12 is an enlarged perspective view of the flange part for medical irrigation tube.

FIG. 13 is a perspective view of the flange part for medical irrigation tube shown in an environment of use; and,
FIG. 14 is a second perspective view of the flange part for medical irrigation tube shown in an environment of use.

The broken lines in FIGS. 1-14 illustrate environmental subject matter only and form no part of the claimed design.

The part shown by the solid line (flange part) is the article sought for a design registration. The flange part is a component of a medical irrigation tube and trocar system for use in endoscopic surgery. The flange part restricts insertion of the medical irrigation tube, so as to provide a constant length of the inserted tube, by abutting against the top surface of the sleeve of the trocar system when the tube is inserted into the sleeve.
